UNITED STATES PATENT OFFICE.

DIMMITT H. MERRILL, OF BUFFALO, TEXAS, ASSIGNOR OF ONE-HALF TO ROBERT O. APPLEGATE, SR., OF TYLER, TEXAS.

UMBRELLA-SUPPORT.

1,205,917.

Specification of Letters Patent. Patented Nov. 21, 1916.

Application filed October 4, 1915. Serial No. 53,972.

To all whom it may concern:

Be it known that I, DIMMITT H. MERRILL, a citizen of the United States, resident of Buffalo, in the county of Leon and State of Texas, have made a certain new and useful Invention in Umbrella-Supports; and I declare the following to be a full, clear, and exact description of the same, such as will enable others skilled in the art to which it 10 appertains to make and use the invention, reference being had to the accompanying drawings, and to letters or figures of reference marked thereon, which form a part of this specification.

15 Figure 1 is a side view of the invention as in use. Fig. 2 is a rear view of the same. Fig. 3 is a detail perspective view of the belt plate. Fig. 4 is a similar view of the back plate. Fig. 5 is a similar view of one of the 20 belt loops.

The invention has relation to umbrella supports, to be attached to and carried by the person without interfering with the use of the arms or hands, and designed mainly 25 for use by laborers in the field, although equally useful for others whose occupation or pleasure calls them into the sunlight for long periods of time.

The invention consists in the novel construction and combinations of parts, as hereinafter set forth.

In the accompanying drawings, illustrating the invention, the numeral 2 designates a belt to be buckled around the waist and to 35 which are attached cross straps 3, 3, said straps, where they cross at the back, passing slidably through oblique perforations 4, 4 of a metal plate 5, located between the shoulder blades and provided with a horizontal perforated lug 6, bent outwardly at right-angles.

The belt has secured thereto, at the rear thereof, a metal plate 7, provided with an outwardly bent portion 8 and a vertical portion 8', the latter portion being provided with an outturned, perforated upper end or lug 9 and a lower outwardly and upwardly turned lug 10, the horizontal portion of said last-named lug having a perforation 10', and 50 the vertical portion thereof having a set-screw 11.

The stem or shank 12 of the umbrella is passed slidably through the alined perforations of the lugs 6, 9 and 10, the set-screw 55 being then engaged with said stem, which

will be held securely in place at the back of the person, but separated by an interval 14 from the hollow of the back, owing to the outwardly bent portion 8 of the belt plate, so that the bearer can bend with ease, free movement of the person in bending being allowed also by the slidable engagement of the shank of the handle with the perforation of the lug 6.

The cross straps are attached at their ends 65 to the belt by means of buckles 15, secured each by a loop 16 to the belt, and are adjusted lengthwise to accord with the height of the person using the device, the back plate being slid upwardly or downwardly to 70 proper position, for the same reason, and being automatically secured or locked in position when the straps are drawn over the shoulders of the wearer. The cross straps may have suitable insertions 18 of elastic 75 webbing therein.

The device is easily attached by slipping the arms through the braces or straps and buckling the belt around the waist, and the umbrella stem and umbrella is as easily secured in position and removed. The device is conveniently detached by slipping the arms out of the braces and unbuckling the 80 waist belt.

I claim:

An umbrella support comprising a belt, brace straps secured at their ends to said belt, a metal back plate carried by said brace straps and provided with an outwardly extending lug having a perforation, a belt 90 plate provided with belt loops and a central standard, said standard having an outward extending portion and an upper portion spaced apart from the belt plate by the length of said outwardly extending portion, 95 said upper portion having an outwardly extending lug provided with a perforation and adjacent thereto a lower outwardly extending lug having also a perforation, said lower lug having a vertical arm, all of the perforations being in alinement and adapted to be slidably engaged by an umbrella stem, said vertical arm having a threaded perforation, and a set screw engaging the same.

In testimony whereof I affix my signature, 105 in presence of two witnesses.

DIMMITT H. MERRILL.

Witnesses:

CHAS. C. EZELL,
B. L. LARRABEE.
